UNITED STATES PATENT OFFICE.

WILLIAM R. MYERS, OF HAMPTON, VIRGINIA.

FIRE-BUCKET.

1,344,557.

Specification of Letters Patent. Patented June 22, 1920.

Application filed October 5, 1918. Serial No. 257,042.

To all whom it may concern:

Be it known that I, WILLIAM R. MYERS, a citizen of the United States, residing at Hampton, in the county of Elizabeth City 5 and State of Virginia, have invented certain new and useful Improvements in Fire-Buckets; and I do hereby declare the following to be a full, clear, and exact description of the invention, such as will enable 10 others skilled in the art to which it appertains to make and use the same.

This invention relates to improvements in fire buckets and especially to that type of bucket designed to constantly hold a 15 supply of chemicals of fire extinguishing properties.

It is one of the objects of the present invention to provide a fire bucket in which the parts are protected not only from the 20 action of the chemicals contained in the bucket by contact with the liquid, but also are protected from the fumes which arise from the chemicals.

Another object of the invention is to provide a bucket of this type in which all of the parts are of extremely simple and, therefore, inexpensive construction and an especial object of the invention is to provide a fire bucket which, while it is hermetically sealed, is capable of being most readily 30 and quickly uncovered to permit the distribution of the chemical contents toward or upon the flaming material, so that the minimum amount of time may be required 35 in preparing the apparatus for use in emergencies.

With these and other objects in view, the invention consists of the construction, the combination and in details and arrangements of the parts as more particularly 40 hereinafter described relative to the embodiment of the invention, illustrated in the accompanying drawings, in which—

Figure 1 is a perspective view of the 45 bucket showing the parts in separated relation, and

Fig. 2 is a central vertical section through the bucket.

The bucket consists of a suitably shaped 50 container made of any desired material and in any proportions and size and is generally indicated at A, the interior of the bucket being provided with a coating B of suitable material designed to resist the 55 action of the chemical contents thereof upon the material of which the bucket may be

constructed. For the purpose of preventing the falling of objects into the bucket and also retarding evaporation or deterioration of the chemical contents a lid C is 60 provided, this being shown in this instance as slightly dished as at 2 downwardly from the top and having a slightly concaved peripheral flange 3, the maximum diameter of the lid being approximately equal to the 65 diameter of the rim bead 4 of the bucket, so that when the cover C is applied to the bucket a portion of the cover projects below the plane of the top of the rim 4.

It is desirable to protect the cover from 70 the fumes or condensed matter from the chemical contents of the bucket and for this purpose there is introduced beneath the cover C a protecting sheet or diaphragm, preferably of pliant sheet material, the 75 nature of which obviously will vary according to the nature of the contents of the bucket, the sheet being indicated at D. A metallic sheet or foil is preferable in many cases, but I am not necessarily limited to 80 the use of a metallic diaphragm or protecting sheet.

To secure the hermetic and effectual connection of the protecting sheet D to the rim of the bucket, I prefer to employ any 85 suitable cement or adhesive agent indicated at 5 to the rim of the bucket, so that when the pliant sheet D is applied flatwise across the top of the bucket, the marginal portion of the sheet, which preferably is cut in the 90 form of a disk, may be pressed into firm contact with the inner side of the rim of the bucket and adhesively connected thereto through means of the adhesive or a cement agent 5. After the protecting sheet D has 95 been laid over the rim of the bucket, the cover C is then lowered into position on top of the sheet and pressed down, so that the sheet is drawn downwardly under tension by the depressed portion 2 of the cover, 100 thereby insuring a substantially complete cementitious joint between the edge of the sheet D where it is engaged and pressed down by the flange 3 of the cover. A substantial air chamber is formed between the 105 dished lid and the tightly stretched sheet, as shown in Fig. 2, which permits expansion of the contents of the bucket and tends to prevent the breaking of the fragile sheet by the accidental denting of the lid. After 110 the cover has been positioned as above indicated, the projecting edge of the protect-

ing sheet D may then be rolled down and under the bead 3 as is plainly indicated in Fig. 2, so as not only to make a neat appearance for the bucket, but also to increase the sealing area of contact between the marginal portion of the sheet D and the bead 4 of the bucket.

From the above, it will be seen that the bucket has a lining which is designed to resist the action of the chemicals contained therein, but also the utilization of a suitable chemical resistant as the sheet D protects the cover C from the fumes which may arise from the chemicals. The cover also may have its under-surface coated as at E with a chemical resistant material if desired. In emergency when the chemicals are to be utilized in the extinguishing of fires the attendant or person using the device may readily dislodge the cover C for the reason that it is not wedged, interlocked or otherwise frictionally or positively interengaged with the rim of the bucket and lies substantially loose on the top of the same, so that it can be removed in minimum time in emergencies. As soon as the cover is thrown off the pliant and relatively fragile sheet D is readily drawn off and the hands may be dipped into the contents to spray a

small quantity on the fire, if desired, or 30 the whole contents of the bucket may be thrown on to the fire if necessary.

What I claim is:

1. In a fire bucket having a chemical resistant inner surface, an outturned rim 35 coated on its inner and upper surface with adhesive material, a lid having an upturned rim adapted to fit resiliently within and upon said rim of the bucket and a pliant fragile protecting sheet interposed between 40 the bucket and the lid, and adapted to be depressed by said rim into said bucket against the inner adhesive coated surface of the bucket.

2. In a fire bucket having a chemical re- 45 sistant inner surface, an outturned rim coated on its inner and upper surface with an adhesive material, a dished lid having an upturned rim, and a pliant fragile protecting sheet interposed between the bucket 50 and the lid and adapted to be depressed by the rim of the lid into said bucket and against the inner adhesive coated surface of the bucket rim leaving an air chamber between said fragile sheet and said dished lid. 55

In testimony whereof I affix my signature.

WILLIAM R. MYERS.
